UNITED STATES PATENT OFFICE

ROBERT G. SEELHOFF, OF CHICAGO, ILLINOIS, ASSIGNOR OF ONE-HALF TO ABNER L. MADSEN, JR., OF CHICAGO, ILLINOIS

DRAPERY ORNAMENT

Application filed March 27, 1928. Serial No. 265,194.

My invention relates to ornaments usually employed for embellishing the decorative value of draperies, valances, over-head carved effects and other furnishings of an ornate 5 character, and more particularly to tassel effects, and my main object is to produce a novel artificial tassel which closely resembles the conventional article.

A further object of the invention is to produce the novel tassel from sheet material, such as metal, and only to the extent apparent in relief, whereby a minimum amount of material may be used.

A still further object of the invention is to 15 give the novel tassel a finish by stamping or pressing which simulates any standard tassel design.

Another object of the invention is to press the novel tassel in hollow and open form, so 20 that its edge may be substantially flat and adapted for the hanging of the tassel against a drapery or other object having a substantially flat surface.

A final, but nevertheless important object 25 of the invention is to form the head piece or top of the novel tassel with an element which enables it to be readily attached or hung in front of a drapery, column or other furnishing.

With the above objects in view and any 30 others that may suggest themselves in the specification and claims to follow, a better understanding of the invention may be gained by reference to the accompanying drawing, in 35 which

Figure 1 is an elevation of a typical drapery furnishing, showing the application of the novel tassel;

Fig. 2 is an enlarged elevation of the tassel, 40 partly broken away;

Fig. 3 is a vertical section; and

Figs. 4, 5 and 6 are detail sections taken respectively on the lines 4—4, 5—5, and 6—6 of Figure 2.

In the art of interior decoration, tassels are 45 given more or less prominence, either in natural form or by being printed upon wallpaper, cloth and the like. My invention concerns the physical or bodily representation of 50 the article, but it is a matter of common

knowledge that tassels of good material are more or less costly. Since many tassels are hung on the faces or fronts of draperies, valances, walls, and other objects presenting a flat or closed appearance, it has occurred to me 55 that a substitute for the commonly expensive tassel could be made of a material so fashioned and decorated that a singular simulation of the real article is the result. This I have accomplished consistent with the above enumerated objects, which are attained to the fullest extent in the novel embodiment.

Referring specifically to the drawing, 10 denotes a typical drapery showing, with any suitable cap or other over-head effect 11. 60 The novel tassel 12 is illustrated as hung in front of the drapery, at two points, such as adjacent to the entrance or parting of the drapery. It will, of course, be understood 65 that the tassel is applicable in the same manner as the standard article at any point along the drapery or the head piece which presents a sufficient backing.

Figure 2 shows an enlarged form of the tassel, decorated to simulate a given design. 70 As shown more particularly in the other views, the novel tassel is composed of a length of sheet material, such as metal, cardboard, celluloid or the like, the same being pressed in hollow and open form. As shown 75 more particularly in Figure 5, the curvature of the stock is of a segmental section, so that the front of the tassel may appear rounded as if in relief, the back being defined by the rim or edge of the material. The said back 80 is preferably cut flat, to enable the tassel to rest against the drapery, wall or other backing object. When so disposed, the form of the novel tassel gives the appearance of the real cloth tassel, which satisfies the decorative 85 requirement of the premises.

It is noted the tassel is pressed with a rope effect medially, a base or source 13 at the upper end, a knot 14 toward the lower end, and the cord group 15 at the bottom. These 90 are the main incidents of the typical tassel, but I have for purposes of illustration shown various other incidents of a minor character stamped in the material for purposes of detailed decoration and it will be obvious that 95

the novel tassel may be formed or decorated with an endless variety of designs as may suit the fancy.

The tassel effect is completed by providing the article with a bottom 16, which as noted in Figure 6, is stamped with points generally grouped to lend the impression of the cord ends as one views the artificial tassel from below. At the top, the base 13 is extended with a downward barb 17 which is used for the suspension of the tassel upon the tapestry, wall or other object, so that no sewing, hooks or other special means need be resorted to for the mounting of the tassel. At the same time, the novel barb 17 enables the tassel to be mounted with one simple movement, saving time and labor in a position which is frequently dangerous or awkward. To mount the tassel it is simply necessary to hold it at the bottom and give it a slight tug as the top is pressed against the backing object.

Thus, the novel tassel, which may be produced at low cost, satisfies a requirement cheaply where it is usually customary to go to considerable expense. When one or more of the artificial tassels are hung as described, a person approaching the same is readily impressed by the ornamental and natural appearance thereof, and receives no suggestion whatever that the tassel is of an artificial or mechanical nature. Obviously, the average person or observer does not extend his observation to the point of scrutiny, so that the intent of the decorator is carried out fully and satisfactorily through the general impression made by the improved tassel. Naturally, my invention is not confined to the particular detail of impressing or decorating the tassel, but rather to the basic structure thereof to produce the desired general effect, as covered in the appended claims.

It is to be noted that the tassel end portion or wall 16 serves to prevent the hollow shell or body from embracing a fold of the curtain and thus destroying the tassel effect. Furthermore, the upper portion 13 of the body is relatively shallow and its edge, as shown in Figure 4, is inset so as to be caused to snugly embrace the drapery through the action of the pin or hook 17. Of course, the edges of the shell will substantially engage the curtain 10 or drapery throughout their entire length, which means that the drapery will merely be compressed slightly at the site of the portion 13. It is also noted that the intermediate edge portions,— for instance at knot 14 are arcuately cut, as indicated in Figure 3, so as to give the simulation of a knot.

I claim:—

1. As a new article of manufacture, a tassel-simulating drapery attachment comprising an elongated shell-like body provid-

ing marginal side flanges adapted to engage the drapery to space the major portion of the attachment outwardly therefrom, an attaching member at the upper end of said body, and the lower end of said body being relatively wider than the intermediate portions thereof and terminating in a tassel-bottom simulating wall adapted to prevent said shell from embracing a fold of the drapery.

2. As a new article of manufacture, a tassel-simulating drapery attachment comprising an elongated shell-like body providing marginal side flanges adapted to engage the drapery to space the major portion of the attachment outwardly therefrom, an attaching member at the upper end of said body, the upper end of said shell comprehending a relatively flat base portion inset from the major portion of said body whereby to snugly engage the drapery at the site of said attaching member, and the lower end of said body being relatively wider than the intermediate portions thereof and terminating in a tassel-bottom simulating wall adapted to prevent said shell from embracing a fold of the drapery.

In testimony whereof I affix my signature.

ROBERT G. SEELHOFF.
